UNITED STATES PATENT OFFICE.

PHILIP LINDEMEYR, OF BALTIMORE, MARYLAND, ASSIGNOR TO THE AMERICAN STOPPER COMPANY, OF NEW YORK, N. Y.

DESIGN FOR A VESSEL-CAP.

SPECIFICATION forming part of Design No. 30,765, dated May 16, 1899.

Application filed April 18, 1899. Serial No. 713,512. Term of patent 7 years.

To all whom it may concern:

Be it known that I, PHILIP LINDEMEYR, of the city of Baltimore and State of Maryland, have invented and produced a new and original Design for Caps for Closing Vessels, of which the following is a specification, reference being had to the accompanying drawings, forming part thereof.

Figure 1 is a perspective of a cap, showing my new design. Fig. 2 is a vertical central section of the same.

The leading feature of my design for a bottle-cap consists in series of longitudinal corrugations 1, situated in the cap-flange 2 and separated by plain faces 3, the corrugations extending near to the periphery 4 of the cap-top, said cap-flange having no continuous in-

ward circumferential depression adjacent the periphery of its top, as in my application for a patent for a design for a bottle-cap of even date herewith.

5 indicates inwardly-extending projections situated in the plain faces 3, intermediate the series of corrugations.

It is apparent that the design is applicable to caps for jars and other vessels.

Having thus described my invention, what I claim is—

The design for a vessel-cap, as herein shown and described.

PHILIP LINDEMEYR.
